Primary Examiner—S. Leon Bashore*Assistant Examiner*—Richard H. Tushin*Attorney*—Melvin A. Crosby[57] **ABSTRACT**

A closed, pressure operated, stock inlet box, especially for a papermaking machine, which has walls supporting the lips of the discharge nozzle. The lip supporting walls of the box are constructed as hollow girders and support for the walls is provided by supporting load relief girders adjacent the walls and confining therewith chambers which are pressurized. The load relief girders, according to the invention, are mounted inside the hollow girders of the walls to be supported thereby leading to a compact structure. Mechanical support elements, ribs, for example, disposed between the load relief girders and the supported walls transmit loads from the walls to the load relief girders in the event of loss of pressure in the pressure chambers.

**PRESSURIZED CHAMBERS FOR CONTROLLING
DEFLECTION OF PAPERMAKING MACHINE
HEADBOX WALLS**

The invention relates to a closed and pressure operated stock inlet box, in particular for paper making machines, and having a discharge nozzle extending over the machine width, the nozzle being defined by an upper and lower lip each of which is supported by one wall of the stock inlet box, and each said wall being formed as a hollow girder.

In modern papermaking machines, which are being constructed with constantly increasing operating speeds and machine widths, the walls of the stock inlet box of the machine are subjected to ever increasing loadings, namely, and in particular, due to the pressure prevailing in the interior of the box. The pressure in a stock inlet box increases, as is known, with the velocity with which the stock jet is discharged from the said discharge nozzle of the stock inlet box. However, the loading due to the dead weight of the stock inlet box is also substantial in the case of large machine widths. These loadings on the stock inlet box result in a corresponding deformation of the walls of the box which, in the case of lip supporting walls, also effect the lips themselves.

To counteract the effect of wall deflection, a known stock inlet box (German Pat. No. 1,461,176) is provided with a load relief girder on the outside of each lip supporting wall, constructed as a cavity girder, and being adapted to support the respective wall against deflection due to internal pressure by means of a pressure chamber, extending substantially over the entire machine width and supplied with a pressure medium. While the above mentioned load relief girder flexes freely due to the internal pressure transmitted from the pressure chamber, the lip supporting wall itself is not stressed at all in bending, in the ideal case when the loading is equal on both sides thereof.

However, the ideal case of equal loading on both sides of the lip supporting wall by no means occurs at all times. For example, it does not occur if the pressure in the pressure chamber collapses. Accordingly, even when employing a load relief girder and a pressure chamber, each lip supporting wall must have a substantial section modulus and must be correspondingly dimensioned. To this end, each lip supporting wall of the above mentioned known stock inlet box is constructed as a hollow girder the side of which facing the inside of the stock inlet box is biased by the internal pressure of the stock inlet box and the side of which facing the exterior bears against the pressure chamber and is biased by the chamber pressure. Accordingly, seen from the side towards the stock inlet box, the cross section of each wall has a certain minimum extension. However, the load relief girder also has cross-sectional dimensions which are not insubstantial. Accordingly, a structural unit of the kind heretofore described and comprising a wall and load relief girder occupies a comparatively large amount of space, which leads to difficulties if the required space is not available.

With the foregoing in mind, a primary objective of the present invention is the provision of a stock inlet box of the nature referred to in which at least one of the walls of the box supporting a lip of the nozzle of the box is supported against deflection but without greatly in-

creasing the cross sectional dimensions of the supported wall.

Another object of the present invention is the provision of a supporting arrangement for a wall of a stock inlet box which supports a lip of the nozzle of the box in which the supporting arrangement is located substantially completely within the normal cross sectional confines of the supported portion of the wall.

Still another object is the provision of a supporting arrangement for a wall of a stock inlet box which supports a lip of the nozzle of the box in which the supporting arrangement employs a pressure medium for effecting the support but wherein loss of pressure of the medium does not result in complete loss of the supporting function of the supporting arrangement.

The foregoing objects as well as still other objects and advantages of the present invention will become more apparent upon reference to the following detailed specification taken in connection with the accompanying drawings, in which:

FIG. 1 shows a stock inlet box for a high speed papermaking machine shown in longitudinal section along the longitudinal axis of the machine.

FIG. 2 is a section taken along the line II-II of FIG. 1 and drawn at enlarged scale and showing a supporting structure comprising hollow girder, load relief girder and pressure chamber.

FIG. 3 is a fragmentary view like FIG. 2, but shows a modified form wherein the hollow girder is open at the ends.

BRIEF SUMMARY OF THE INVENTION

According to the invention the problem is solved in that the load relief girder and the pressure chamber associated therewith are disposed within the wall which is constructed as hollow girder. The load relief girder is thus completely surrounded by the stock inlet box wall which is constructed as a hollow girder so that the space requirements of a stock inlet box constructed in accordance with the invention and, as seen from the side, is no greater than that of a conventional stock inlet box which has no load relief girder and no pressure chamber.

It is of no consequence whether the hollow girder forming the affected wall of the stock inlet box is constructed in totally enclosed form or if it has apertures on the end faces and/or on the side opposite to the interior of the stock inlet box. A hollow girder which is open at the end faces will be used in a preferred embodiment since it is then very simple to install the load relief girder. The hollow girder forming the wall of the stock inlet box may, however, also be comprised of a plate, facing the interior of the box, and of two stiffening members disposed in longitudinally spaced relation on the exterior of the plate and between which the load relief girder is accommodated.

The idea of the invention may be applied to the front wall which supports the upper lip of the nozzle as well as to the wall supporting the lower lip of the nozzle and forming the bottom wall of the stock inlet box. In the first mentioned case, the stock inlet box is shortened, over prior art constructions, in the direction corresponding to the longitudinal machine orientation while, in the other case, a corresponding reduction is obtained in the structural height of the stock inlet box. It is, of course, possible for both the front wall and the bottom

wall of the stock box to be constructed in accordance with the invention.

The manner in which the load relief girder is mounted in the appropriate hollow wall girder of the respective wall of the stock inlet box is of no consequence for the method of operation of the entire supporting structure provided the mounting of the load relief girder is located exclusively in the region of the load relief girder ends, in order to ensure completely free flexure of said load relief girder. For example, the ends of the load relief girder may be welded directly to the end faces of the hollow girder, for example to end flanges which are common to the hollow girder and the load relief girder. However, such construction causes the welding seams to be simultaneously stressed in tension and bending and, therefore, result in a relatively unfavorable form of loading. To avoid this unfavorable condition and, in accordance with a further idea of the invention, it is proposed that the connection between the hollow girder of the wall of the stock inlet box and the load relief girder associated therewith, be provided exclusively by tie elements disposed at the ends of the load relief girder. Such tie elements may, for example, be relatively thin plates which therefore have flexural elasticity and which do not offer any substantial resistance to the bending moment developed thereon which occurs when the load relief girder is formed. Welded joints, in such an arrangement, are, in practice, stressed only in tension.

In the event that the pressure in the pressure chamber collapses during operation of the papermaking machine it is advantageous for spacers to be disposed within the pressure chamber between the lip supporting wall of the stock inlet box and the load relief girder pertaining thereto, the height of said spacers being preferable identical to the internal width of the pressure chamber when the wall of the stock inlet box is in the unpressurized state on both sides of the wall. Accordingly in the previously mentioned emergency, namely, when there is a loss of pressure in the pressure chamber, it is possible for the affected wall of the stock inlet box to bear directly on and be supported by the load relief girder. In such a case, the section moduli of the wall of the stock inlet box and of the load relief girder will be additive so that the flexure of the wall of the stock inlet box remains within tolerable limits.

DETAILED DESCRIPTION

The stock inlet box of FIG. 1 is provided with a front wall 1 and a bottom wall 2, both constructed in accordance with the invention, also a stiffened rear wall 3, lateral walls indicated by 3a, a cover 4, a traversing transmission 5 for the vertical adjustment of the front wall 1, and an inlet chamber 6. A discharge nozzle 20, extending over the entire width of the stock inlet box and having a lower lip 21 and an upper lip 22 is formed from the front wall 1 and the bottom wall 2. Perforated rollers 7 and an overflow trough 9 are also provided in the interior of the box.

As can be seen, the front wall 1 is constructed as a hollow girder which completely surrounds a load relief girder 10. A pressure chamber 12, extending over the entire width of the stock inlet box and having a connection, not shown, for a pressure medium, for example, water is confined between the said load relief girder 10 and that part of the front wall 1 which faces the interior of the stock inlet box. The internal pressure in the stock

inlet box bears on the internal surface of the front wall 1 and is transmitted via the pressure medium in the pressure chamber 12 to the load relief girder 10. The surface offered by the front wall 1 to the internal pressure is, of course, somewhat larger than that part of the front wall which is biased by the chamber pressure. However, since the pressure in the pressure chamber 12 can be adjusted to a value exceeding the internal pressure in the stock inlet box, that part of the front wall 1 which faces the interior of the stock inlet box, and therefore the upper lip 22 of the discharge nozzle are practically free of flexure; only the load relief girder 10 is deformed.

The stock inlet box wall supporting the lower lip 21, namely, the bottom wall 2 is constructed in the same manner as the front wall 1 in the form of hollow girder means. Two hollow girders 30 and 31 of box-shaped cross section are fixed to the underside of bottom wall 2, each said hollow girder surrounding one load relief girder 32. A pressure chamber 34 is provided between each load relief girder and the respective hollow girder, each chamber being supplied by a pressurized medium from means 34a.

As can be seen from FIGS. 2 and 3, the connection between the bottom wall 2, constructed as hollow girder, and the load relief girder 32 associated therewith, is formed by two tie elements 36 and 37. These are provided at both ends of the entire supporting structure and are constructed as flexurally elastic but inextensible plates. Spacers 38 and 39, the height of which is equal to the internal width of the pressure chamber when no pressure is applied to both sides of the bottom are disposed within the pressure chamber 34 on the said bottom wall 2. In the event of loss of pressure in the pressure chamber it is, therefore, possible for the said spacers directly to support the bottom wall 2 on the load relief girder 32. Two of the aforementioned spacers 38 extend along the fore and aft edges of each load relief girder, parallel to the longitudinal extension thereof and also serve for the mounting of resilient sealing strips 40 which seal the sides of the pressure chamber 34. The hollow girder forming the front wall 10 is provided in a like manner with spacers and sealing strips. However, these are not provided with reference symbols in the drawing.

The hollow girder 30 illustrated in FIG. 2 is enclosed all round, that is to say it is also enclosed at its end faces. By contrast, the hollow girder 30a, illustrated in FIG. 3, differs therefrom in that its end faces are constructed in open form in order to simplify the installation of the load relief girder. The pressure chamber disposed between the upper side of the load relief girder 32 in FIG. 3 and the underside of bottom wall 2 of the stock inlet box is, of course, sealed on all sides to permit pressure to be developed therein.

Modifications may be made within the scope of the appended claims.

What is claimed is:

1. In a closed and pressure operated stock inlet box, especially for a papermaking machine, and having confining front, rear, and bottom walls and a laterally extending discharge nozzle, said nozzle comprising upper and lower lips, the upper lip of said nozzle extending from and supported by said front wall of said stock inlet box, and said lower lip extending from and supported by said bottom wall, hollow girder means extending transversely of the stock inlet box and connected to

said lip supporting walls on the sides of said walls which face away from said stock inlet box from imparting stiffness to said lip supporting walls, at least one transversely extending load relief girder means disposed inside a respective hollow girder means and substantially coextensive therewith in the longitudinal direction, connecting means connected between the periphery of said load relief girder means and the respective said wall and confining a closed pressure chamber between the respective lip supporting wall and the side of the relief girder means facing the said wall, said connecting means permitting said relief girder means to flex relative to the respective said wall in the region of said relief girder means between the ends thereof, and means for supplying a pressure medium to said chamber for supporting the respective wall against deflection due to pressure inside said stock inlet box.

2. A stock inlet box according to claim 1 in which the connection of the ends of said load relief girder means to said hollow girder means comprises flexible inextensible elements.

3. A stock inlet box according to claim 2 in which said flexible elements seal said pressure chamber at the ends, and seal members along the sides of said chamber which are elongatable so as not to interfere with flexing of the respective said load relief girder means.

4. A stock inlet box according to claim 1 in which

10
15

said hollow girder means are open at at least the ends thereof.

5. A stock inlet box according to claim 1 which includes spacer means disposed in said chamber between the respective lip supporting wall and the side of the load relief girder means facing the wall and free of at least one thereof and operable for transmitting loads from the said wall to the load relief girder means in the absence of pressure in said pressure chamber.

6. A stock inlet box according to claim 4 in which said spacer means are distributed in said pressure chamber and are dimensioned so as to engage both the said wall and the said load relief girder means when the said wall is free of pressure on both sides thereof.

7. A stock inlet box according to claim 1 which includes at least one said load relief girder means inside the hollow girder means for each of said lip supporting walls of the stock inlet box.

8. A stock inlet box according to claim 1 in which the stock inlet box wall supporting the lower lip of the nozzle forms the lower wall of the stock inlet box, said hollow girder means for said lower wall comprising a pair of hollow girders spaced longitudinally along the lower wall, and a said load relief girder means inside each said hollow girder of said lower wall.
